CLAIM

The ornamental design for actuator for use with central
locking systems controlling doors, trunk and fuel filler
cap of a motor vehicle, as shown and described.

DESCRIPTION

FIG. 1 is a front and upper right perspective view of an
actuator for use with central locking systems controlling
doors, trunk and fuel filler flap of a motor vehicle
showing my new design;

FIG. 2 is a front and upper left perspective view
thereof;

FIG. 3 is a side elevation from right;

FIG. 4 is a plan view from beneath;

FIG. 5 is a side elevation from left;

FIG. 6 is a plan view from above;

FIG. 7 is a front elevation; and,

FIG. 8 is a rear elevation.
